UNITED STATES PATENT OFFICE.

ARTHUR HIRST, OF SHEFFIELD, ENGLAND, ASSIGNOR OF ONE-HALF TO GEORGE HARRY OXLEY, OF SHEFFIELD, ENGLAND.

CUTLERY-GRINDING MACHINE.

Application filed October 13, 1921, Serial No. 507,514, and in Great Britain October 23, 1920.

This invention relates to cutlery grinding machines, its object being to provide improved means for enabling the complete surface of a table knife or like blade to be ground to a contour approximating to that usually ground by hand and at the same time the cutting edge to be ground as a straight edge for the desired length and with such degree of sharpness as may be desired.

10 An ordinary table knife blade tapers both from back to cutting edge and from bolster to point, which is usually rounded, the cutting edge being straight throughout practically the whole length. The longitudinal 15 taper is not even throughout, being most pronounced at the back and barely discernible at the edge; it is also more gradual at the point than at other parts of the blade, so that the transverse taper near the point is 20 even less pronounced than it would be if the longitudinal taper were even. Further, whilst the point portions usually have nearly a flat surface, the blade is preferably somewhat convex transversely near the bolster 25 and at the middle.

Now in cutting a recess, conforming to the tapers in such a table knife blade, whether in the circumference of a rotary blade holder, or in the surface of a plane holder, it is 30 found that if the recess be sunk sufficiently deep at the point end for the complete blade surface to be ground at that end, the recess will be so deep at the bolster end that the cutting edge at this end will not be sharpened but will be of substantial thickness 35 after both sides of the blade have been ground, although the blade may thereby be ground with a straight cutting edge. If, on the other hand, the bolster end of the recess 40 be sunk only so deep that the cutting edge is sharpened at this end it is found that the point end of the recess is so shallow that the boundary of the recess corresponding to the cutting edge of the blade extends from the 45 bolster in a straight line only for a portion of its length and then merges into the surface of the holder to join the point (or even the back) portion of the recess in a line which resembles a spear point across the 50 shallower end of the recess. The result of grinding a blade clamped in such a recess is that instead of grinding its complete surface a portion of that surface will be entirely removed and the cutting edge will be 55 ground to a spear point, or only the point

portions of the surface will be ground.

According to the present invention a cutlery or like blade is held in a grinding machine with its point end twisted about a substantially longitudinal axis. The blade holder is provided with a recess for each blade to be ground, formed as described above with the bolster end sunk only so deep that the cutting edge of the blade is sharpened at this end. The recess will thus have 60 longitudinal and transverse tapers, similar to those required in the blade, merging into the surface in a line across the shallower end of the recess and means are provided for holding a blade in each recess with its point 65 twisted or bent over that line. The blade holder may also be recessed on the other side of that line, preferably with opposite tapers, in order that a greater amount of twist may be imparted to the blade than would otherwise be possible, this additional recessing being specially necessary if the holder is not a 70 cylindrical one designed to rotate. Channels to carry cooling fluid to the back of the blades during the grinding operation are 75 preferably formed in the blade holder across the recesses therein.

In the accompanying drawings:—

Figure 1 is a radial section through a cylindrical blade holder of a grinding machine, 80 recessed for the reception of a blade according to the present invention, the section being taken on the line 1—1 of Figure 2, which is a plan of part of the blade holder.

Figures 3, 4, and 5 are transverse sections 90 taken respectively on the lines 3—3, 4—4 and 5—5 of Figure 2.

Figure 6 is a view similar to Figure 1 with a blade clamped in the recess ready to be ground.

Figure 7 is an elevation of the cylindrical blade holder mounted in a suitable grinding machine.

Like reference numerals indicate like parts throughout the drawings.

A cylindrical blade holder 1 is illustrated in Figure 7. It is rotatably mounted in bearings 11 and is rotated from any suitable source of power. A grinding wheel 12 is mounted in bearings 13 with its axis substantially parallel to that of the blade holder 1. The grinding wheel may be adjusted and fed towards the blade holder 1 by means of a handle 14 operating a screw 15. The grinding wheel 12 is preferably driven at a con- 110

siderably greater speed than the blade holder 1, and during the grinding operation it may if desired be reciprocated on the slide 16 in a direction parallel to its axis.

5 The blade holder 1 is provided with a series of recesses 2 around its circumference, each recess having longitudinal and transverse tapers similar to those required in the blade after grinding. Each of the recesses 2 is sunk only so deep at the bolster end that the cutting edge of the blade 3 will be sharpened at this end as indicated in Figure 5, (the blade 3 being shown in dotted lines in Figures 2, 3, 4, and 5). The result will be 10 that the longitudinal and transverse tapers of each recess 2 will merge into the surface of the holder 1 in a line 4 (Figure 2) which crosses the shallower end of the recess. The boundary of the recess 2 corresponding to 15 the cutting edge of the blade 3 thus extends from the bolster end in a straight line 5 only for a portion of its length, being continued by the line 4 which joins the boundary corresponding to the back of the blade at the 20 shallow or point end of the recess. Preferably, however, the holder 1 is recessed also on the other side of the line 4 as shown at 6, the recess 6 being formed with tapers opposite to those on the other side of the line 4.

25 The boundary of the recess 6 corresponding to the cutting edge of the blade is preferably formed as a straight line extension of the corresponding part 5 of the recess 2. It will be appreciated that in cutting such a recess 30 the line 4 will not necessarily be sharply defined although there will be a slight eminence or ridge in the base of the recesses 2, 6, the position of which is approximately defined by the line 4.

35 Each of the blades 3 is clamped in a recess 2 at the bolster end, but its point end is twisted about a substantially longitudinal axis so that whilst its back remains in the recess 2 its cutting edge towards the point 40 is brought nearer to the holder into the recess 6, thus bending the blade approximately over the line 4. The blades 3 may be thus clamped and twisted by any desired mechanical means. It is, however, preferred to 45 clamp and to twist the blades 3 in the holder 50 1 by magnetic means. For this purpose the cylindrical holder 1 is formed with a spiral groove 7, crossing the recesses 2, 6. An insulated electric conductor 8 is wound round 55 the blade holder 1 in the groove 7 and its ends are brought out and secured to terminal rings in known manner, whereby an electric current may be passed through the conductor 8 whilst the blade holder 1 is rotated 60 in the grinding machine. The insulated conductor 8 is conveniently protected by a filling 9 in the groove 7 of some suitable material such as lead. It is found that with such a construction a current of about two hundred 65 amperes at fifteen volts will induce

sufficient magnetic force securely to clamp the blades 3 in the recesses 2, and to twist their point ends into the recesses 6. The blades 3, thus clamped and twisted on the cylindrical revolving holder 1 are ground 70 in any suitable design of grinding machine. The twisting of the blade not only allows the cutting edge to be ground sharp as a straight edge but also enables the complete surface of the blade to be ground to the desired contour, for the convexity ground on the point portion of the blade will become more or less a plane surface when the blade is released and returned to its untwisted shape. The degree of sharpness imparted 75 to the blade is governed by the depth of the recesses 2, 6 and the feed of the grinding machine.

80 The filling 9 in the spiral groove 7 is preferably arranged to be below the edges of the groove so that a series of channels 10 (Figure 2) are formed across the recesses 2, 6. When mechanical means for clamping and twisting the blades are provided it is still preferred to form channels such as 10 across the recesses 2 and 6, the function of the channels 10 being to carry cooling fluid to the back of the blades 3 during the grinding process and thus to reduce the liability of the blades to be burnt or over-heated by the 85 grind-stone.

90 When mechanical means for clamping and twisting the blades are employed the blade may be forged of extra length or with a tang or the like at the point end to enable the twist to be applied. The extra length or tang would be cut off after the blade had been ground on both sides. Or, the part of the point which is clamped may be ground 95 in a subsequent operation. It will be appreciated that after the blades have been ground on one side they are transferred to a second holder with similar recesses and clamping means adapted to hold the blades for their other sides to be ground. The recesses in the second holder would, of course, also be shallower than the recesses in the first by the reduction in thickness of the blade effected in the first grinding operation.

100 By varying the amount of twist imparted to the blade the shape of the cutting edge which will be ground may be altered and by increasing it beyond the amount required for a straight edge it is possible to grind and sharpen an edge with a concave bend.

105 In the case of a cylindrical blade holder the recess 6 may be dispensed with in some cases, the curvature of the holder enabling the required twist to be imparted to the 110 blades.

Having described my invention, what I claim, and desire to secure by Letters Patent, is:—

115 1. A cutlery grinding machine including

means for holding a cutlery or like blade therein with its point end twisted about a substantially longitudinal axis to impart a convex shape to its surface whilst being 5 ground, substantially as specified.

2. In a cutlery grinding machine, the combination of a blade holder comprising two relatively inclined supporting surfaces meeting in a ridge, means for locating a blade 10 on one of the surfaces with the ridge extending from the back edge of the point to the cutting edge towards the tang end, and means for twisting or bending the blade into a convex shape over the ridge and for holding 15 it thus distorted whilst being ground, substantially as specified.

3. In a cutlery grinding machine, the combination with a blade holder having a recess therein formed with a wall against which 20 the back edge of the blade is placed to locate the cutting edge thereof and with a base to support the blade comprising two relatively inclined surfaces meeting in a ridge extending from the point supporting 25 portion at the locating wall towards the edge supporting portion at the tang end, means for twisting or bending the blade into a convex shape over the ridge, and means for holding it thus distorted in contact with the 30 base of the recess whilst being ground, substantially as specified.

4. In a cutlery grinding machine, the combination of a grinding wheel, means for rotating it, a blade holder, means for moving 35 it repeatedly in a path adjacent to the grinding wheel, the blade holder having a recess therein formed with a wall to locate the cutting edge of a blade and with a base to support the blade comprising two relatively inclined surfaces meeting in a ridge extending 40 from the point supporting portion at the locating wall to the cutting edge supporting portion at the tang end, the one of said surfaces to support the tang end of the blade 45 being inclined to the path of the blade holder in a manner corresponding to the longitudinal and transverse tapers required in the blade and the locating wall of the recess being sunk to approximately half the thickness of the blade edge, means for twisting or bending a blade in a convex 50 shape over the ridge of the recess and means for holding it thus distorted in contact with the base of the recess whilst being ground, substantially 55 as specified.

5. In a cutlery grinding machine, the combination of a grinding wheel, means for rotating it, a blade holder, means for moving it repeatedly in a path adjacent to the

grinding wheel, the blade holder having a recess therein formed with a wall against which the back edge of the blade is placed to locate the cutting edge of a blade and with a base to support the blade comprising two relatively inclined surfaces meeting in a ridge extending from the point supporting portion at the locating wall to the cutting edge supporting portion at the tang end, the one of said surfaces to support the tang end of the blade being inclined to the path of the blade holder in a manner corresponding to the longitudinal and transverse tapers required in the blade and the locating wall of the recess being sunk to approximately half the thickness of the blade edge, 60 means for twisting or bending a blade into a convex shape over the ridge of the recess, means for holding it thus distorted in contact with the base of the recess whilst being ground and a series of channels across the 65 recess to carry cooling fluid, substantially as specified.

6. In a cutlery grinding machine, the combination of a grinding wheel, means for rotating it, a cylindrical blade holder, means for rotating it with its periphery moving in a path adjacent to the grinding wheel, the blade holder having a series of recesses therein each formed with a wall to locate the cutting edge of a blade and with a base to support the blade comprising two relatively inclined surfaces meeting in a ridge extending from the point supporting portion at the locating wall to the cutting edge supporting portion at the tang end, the one of said surfaces to support the tang end of the blade being inclined to the path of the blade holder periphery in a manner corresponding to the longitudinal and transverse tapers required in the blade and the locating wall of the recess being sunk to approximately half the thickness of the blade edge, means for twisting or bending a blade into a convex shape over the ridge of each recess, means for holding it thus distorted in contact with the base of the recess whilst being ground, said bending and holding means comprising a spiral groove around the circumference of the blade holder crossing the series of recesses therein, an insulated electric conductor in the spiral groove, a protective filling in the groove below the edges thereof and means for leading an electric current to the conductor, substantially as specified. 100

In witness whereof I have hereunto set my 105 hand.

ARTHUR HIRST.
